ATTY.

UNITED STATES PATENT OFFICE.

UTAKICHI KAWASAKI, OF SAN FRANCISCO, CALIFORNIA.

CHECK.

1,403,168.

Specification of Letters Patent. Patented Jan. 10, 1922.

Application filed December 15, 1919. Serial No. 345,027.

To all whom it may concern:

Be it known that I, UTAKICHI KAWASAKI, a subject of the Emperor of Japan, residing at San Francisco, in the county of San Francisco and State of California, have invented new and useful Improvements in Checks, of which the following is a specification.

My invention relates to improvements in bank checks, drafts or similar monetary instruments, and resides in the provision of an instrument of this character which is not subject to "raising" or fraudulent "alteration."

One of the objects of my invention is to provide a monetary instrument of the character described in which the payee's name, figures, and other indicia by which the value of the instrument is determined or any indicia which might be fraudulently altered, all appear in imperforate unmarked form surrounded on all of the margins of all of the characters of such indicia by perforations, which perforations define the margins of the characters of the indicia and make fraudulent alteration without detection impossible.

In the present embodiment of my invention as shown in the drawing 1 designates a bank check of usual form save for the features of my invention embodied therein.

30 The payee's name on said check is impressed or imprinted on the check in preferably imperforate unmarked letters 2 and surrounding these letters and defining the margins thereof so as to fill up all of the spaces 35 immediately around them are perforations 3

formed in any suitable manner in said check. The amount indicia at 3', the check number 4 and the written out amount indicia at 5 are likewise formed with imperforate characters 6, 7 and 8 respectively surrounded by marginal perforated portions 9—10 and 11. The perforated portions are divided into squares or blocks separated by lines of imprint designated 13. Other indicia may be formed as hereinbefore described and it will be seen 45 that by having perforated portions in the check or instrument, defining the letters or numbers it will not be possible to fraudulently alter the indicia by filling in the perforations as is sometimes done where the indicia is of perforated characters.

The characters in thus being surrounded by perforations which fill up the imprint so as to leave no space between two adjacent characters or groups thereof or between two 55 lines cannot be altered or changed by "cutting out" or filling up the perforations and imprinting other characters or by imprinting characters between the originally imprinted characters, without mutilating the check. 60

I claim:—

A bank check having certain indicia thereon in imperforate form and perforations in said check surrounding and defining the margins of the characters of the indicia, and 65 lines of imprint between the characters of the indicia separating the perforations into blocks surrounding each character.

UTAKICHI KAWASAKI.
